Primary Examiner — Garth Rademaker*Assistant Examiner* — Aaron C Fowler(74) *Attorney, Agent, or Firm* — Dunlap Bennett & Ludwig, PLLC**CLAIM**

The ornamental design for a knee supporting walker, as shown and described.

DESCRIPTION

FIG. 1 is a front elevation view of the knee supporting walker showing my new design;

FIG. 2 is a rear elevation view thereof;

FIG. 3 is a left side elevation view thereof;

FIG. 4 is a right side elevation view thereof; and,

FIG. 5 is a top plan view thereof.

The broken lines shown in the drawings illustrate portions of the knee supporting walker that form no part of the claimed design.
